UNITED STATES PATENT OFFICE.

HENRY LIEBBE, OF DES MOINES, IOWA.

SMOKE-CONSUMING BRIDGE-WALL CAP.

SPECIFICATION forming part of Letters Patent No. 398,415, dated February 26, 1889.

Application filed October 29, 1888. Serial No. 289,458. (No model.)

To all whom it may concern:

Be it known that I, HENRY LIEBBE, a citizen of the United States, residing at Des Moines, in the county of Polk and State of Iowa, have invented a new and useful Smoke-Consuming Bridge-Wall Cap, of which the following is a specification.

My invention relates to a device to be used in connection with the construction of boilers and heating-furnaces generally where the combustion-chamber is inclosed on the fourth side with what is commonly termed the "bridge-wall," and is for the purpose of producing a nearly-perfect system of combustion of the escaping particles of carbon set free in the combustion of coal, which usually pass off unconsumed through the flue or chimney and produce what is termed "black smoke," which is not only a great loss and waste of fuel, but also highly objectionable from a sanitary and aesthetic standpoint to the residents of cities where coal, and especially soft or bituminous coal, is largely used in both power and heating plants. As heating-furnaces are ordinarily constructed the air-supply to support combustion is taken through the grate; and whereas it is a recognized fact that this is inadequate for perfect combustion and that some air admitted above the grate is a great advantage, various devices and contrivances have been resorted to for the purpose of so introducing atmospheric air, and usually at or near the bridge, but thus far only with slight success, due to the fact that inventors have either not known or failed to supply the air so introduced at a sufficiently-heated state. Experiments show that the carbon and hydrogen set free in combustion will not combine with the oxygen of the air until the latter is raised to from 600° to 800° Fahrenheit, and at that temperature ignites and burns, and thus prevents a waste of fuel and avoids black smoke. Hence the object of my invention is to supply air to a furnace sufficiently heated to enable the oxygen of the air to combine with the carbon and hydrogen contained in the smoke to support perfect combustion. I accomplish this by the device shown at A, Figure 1.

Fig. 1 is a cross-section of an ordinary tubular boiler and its setting, showing an ele-

vation of bridge-wall cap at A. Fig. 2 shows a cross-section of bridge-wall and cap on line B C. Fig. 3 is a horizontal section of bridge-wall cap on line D E, and Fig. 4 shows a cross-section of tubes on line x y.

Similar letters refer to similar parts throughout the several views.

The cap contains air-passages a, b, and c, separated from each other by partitions 1 and 2. In the top shell of cavity c a series of openings are provided, (marked h,) over which are set portable hollow teeth d d d and c, all as shown.

The operation of the cap is as follows: The bridge-wall being built hollow and said hollow having air-supply passages in any manner, or as at I I, the air flows into cavity a through openings e e, thence flows to right and left into cavity b through openings f f in partition 2, thence through cavity b into cavity c through openings g g in partition 1. From this cavity the air will flow upward through openings h h h h in top shell of cavity c, then into the hollow cavity of teeth d d d, the form of the cavity in said teeth being such as will deflect the air to a horizontal direction to rear, all as indicated by arrows. By this arrangement the air flows through the successive cavities and becomes heated in its course by being confined therein until it issues out from back edge of the hollow teeth and in numerous vertical streams directly over the bridge, where the gases of combustion are most dense. The cap and teeth being exposed externally to the direct rays of the fire and the products of combustion, their temperature is raised to a high degree, but they do not become consumed or burned by reason of the continual unobstructed flow of air from within, which results in burning the carbon and hydrogen in the smoke completely without any detrimental results, which is the object desired.

The form of teeth is such that as the gases pass through between them the vacuum-forming tendency accelerates the flow of hot air from their cavities.

I purpose constructing the cap of such materials as will best resist the action of the fire—such as iron, aluminum, plumbago, and fire-clay—to suit special cases.

¶ I am aware that hollow bridge-walls, bridge-wall plates, &c., have been used prior to my invention. I do not therefore claim the same, broadly; but

5 What I claim is—

1. In a smoke-consuming furnace, the bridge-wall cap having circulating-chambers *a b c*, with partitions 1 and 2, connecting with each other by openings *f f* and *g g* through
- 10 partitions 1 and 2, in combination with openings *h h h* and hollow tubes or teeth *d d d d*.

2. In a smoke-consuming furnace, the bridge-wall cap provided with hollow tubes or teeth for diffusing the heated air, the form of teeth as shown, with open back and curved cavity to deflect the outflowing current to a horizontal direction, all substantially as shown. 15

HENRY LIEBBE.
